UNITED STATES PATENT OFFICE.

DANIEL P. PRESCOTT, OF VERNON, VERMONT, ASSIGNOR OF ONE-HALF TO
MARCUS M. BEEMAN, OF SYRACUSE, NEW YORK.

NUT-LOCK.

SPECIFICATION forming part of Letters Patent No. 252,295, dated January 10, 1882.

Application filed September 6, 1881. (No model.)

To all whom it may concern:

Be it known that I, DANIEL P. PRESCOTT, a citizen of the United States, residing at Vernon, in the county of Windham and State of Vermont, have invented new and useful Improvements in Nut-Locks, of which the following is a specification.

This invention relates to the construction of an improved nut-lock adapted to both iron and wood work, and to washers to be used with said nut-locks under certain circumstances, the object being to provide a strong and surely-fastening nut-lock, which can be effectually secured to an iron seat against turning back by the use of such tools as mechanics are usually supplied with, and can, by the use of the same tools, be so freed as to be easily removed from its bolt, and which can, with suitable washers, be positively secured against unscrewing when used on wood-work.

In the drawings forming part of this specification, Figure 1 is a perspective view of the under side of a nut provided with locking devices constructed according to my invention. Fig. 2 is a plan view of the under side of said nut. Fig. 3 is a side elevation of said nut and a washer, the latter being shown in section. Fig. 4 is a perspective of the upper and Fig. 5 of the under side of the washer. Fig. 6 is a view of the spring-pawl removed from the nut, and Fig. 7 is a side elevation of a section of a rail-joint having said nuts thereon.

In the drawings, A is the nut. e is the spring-pawl. c is the washer. b is the section of a rail. d is the joint-plate.

In constructing my improved nut-lock I make the spring-pawl e of steel or other suitable wire, bending it in the form shown, thereby providing a short arm, e², standing at, or nearly at, right angles to its longer curved body e³, the general form of said body being very clearly shown in Fig. 1.

To adapt the nut A to receive in its under face said spring-pawl e, said nut is bored in a vertical direction on its under side to receive the arm e² of the spring-pawl, and from one side of the hole bored to receive said arm a curved channel is formed, leading from said hole to one side of the nut, one-quarter around

the latter, of sufficient depth to receive within it the curved arm e³ of said spring-pawl, into which the latter is driven, taking the position in nut A indicated in the drawings, the end of said long arm standing up above the surface of the bottom, as in Fig. 1, and projecting somewhat beyond the side of said nut.

In Fig. 1 it will be plainly seen that the end of pawl e at the side of the nut stands up away from the bottom of the groove in said nut, allowing the end of said pawl more or less spring motion at that point, and said pawl is placed in nut A in such a position that when said nut is turned onto a bolt the projecting end of said pawl will draw over the surface of the object against which the nut is screwed.

Figs. 4 and 5 illustrate the washer, which is adapted to be used on certain descriptions of work with said nut-lock, as hereinafter described, said washers c being made with grooves x on their upper faces and with pointed studs v on their under sides.

In using my improved nut-lock on iron-work ordinarily the washer c may often be dispensed with, as illustrated in Fig. 7. There it is shown that the nut A is screwed directly against the joint-plate d, in the face of which, within the circle described by the end of the pawl e, a slight notch, o, is cut with the point of a cold-chisel. Thus when the nut has been firmly screwed down the end of pawl e springs into said cut or notch o and effectually prevents said nut from turning back. In some situations where said nuts are used on finished work and it is desirable not to mutilate the face thereof, the washers c are used, and the studs v on said washers prevent the latter from turning on the surface of the object against which they may be forced by the nut, and the end of the pawl e, falling into the grooves (or one of them) on the face of said washer, as in Fig. 3, prevents the nut from turning off. In using said nut-locks on wood-work they are used with said washers preferably in the manner just described. To turn said nuts off, the end of a chisel or some similar thin-edged instrument is pressed under the projecting end of the pawl e, slightly raising the end of the latter and disengaging it from a groove in washer c or from

the notch *o*, when the nut may be easily unscrewed.

From the fact that the end of pawl *e* may have more or less motion, or that the nut and the object against which it is screwed may under some circumstances slightly change their relative positions without causing the end of said pawl to be disengaged from the groove or notch into or against which it springs constantly, it is obvious that the within-described nut-lock possesses many advantages over other nut-locks in use.

What I claim as my invention is—

The within-described improved nut-lock, con-

sisting of the nut *A*, and the pawl *e*, said nut being provided on its under face with a single vertical socket to receive the short arm of said pawl, and with a groove to receive the downwardly-inclined long arm thereof, reaching from said socket beyond the sides of said nut, the combination and arrangement of said nut and pawl being substantially as and for the purpose set forth.

DANIEL P. PRESCOTT.
